VACUUM CLEANER ATTACHMENT FOR A HAIR CLIPPER

Mathew Andis, Racine, Wis., assignor to Andis Clipper Co., Racine, Wis., a corporation of Wisconsin

Continuation of design application Ser. No. 87,168, Sept. 27, 1965. This application May 10, 1966, Ser. No. 2,244

Term of patent 14 years

(Cl. D9—2)

FIG. 1

FIG. 2

FIG. 3

FIG. 4

FIG. 5

FIG. 6

FIG. 1 is a front perspective view of a vacuum cleaner attachment for a hair clipper showing my new design.

FIG. 2 is an enlarged elevational view thereof.

FIG. 3 is a top plan view thereof.

FIG. 4 is a rear end elevational view thereof.

FIG. 5 is a front end elevational view thereof.

FIG. 6 is a view thereof taken in cross section on the line 6—6 of FIG. 3.

The broken line showing of the hair clipper in FIG. 1 is for illustrative purposes only.

This application is a continuation of my copending application Serial No. D. 87,168, filed September 27, 1965 and now abandoned.

I claim:

The ornamental design for a vacuum cleaner attachment for a hair clipper, as shown and described.
